UNITED STATES PATENT OFFICE

131,154

DESIGN FOR A BUILDING UNIT

Robert Lee Kaye, Newark, N. J.

Application April 5, 1941, Serial No. 100,172

Term of patent 14 years

To all whom it may concern:

Be it known that I, Robert Lee Kaye, a citizen of the United States of America, residing at Newark, in the county of Essex and State of New Jersey, have invented a new, original, and ornamental Design for Building Unit, of which the following is a specification, reference being had to the accompanying drawing, forming part thereof.

In the drawing:

Fig. 1 is a plan view of a building unit, showing my new design.

Fig. 2 is a sectional view thereof along the line 2—2 in Fig. 1 drawn at twice the scale in Fig. 1 and with the small horizontal ribs and depressions shown full size for clarity.

I claim:

The ornamental design for a building unit, as shown and described.

ROBERT LEE KAYE.
